UNITED STATES PATENT OFFICE.

JOHN A. PILCHER, OF ROANOKE, VIRGINIA.

CAR CONSTRUCTION.

Application filed April 26, 1922. Serial No. 556,651.

To all whom it may concern:

Be it known that I, JOHN A. PILCHER, a citizen of the United States, residing at Roanoke, in the county of Roanoke and 5 State of Virginia, have invented certain new and useful Improvements in Car Construction, of which the following is a specification.

This invention relates to improvements in 10 car construction, and has among its objects to provide an arrangement of car body and car door wherein the doors may be held shut in a simple and direct manner, and by means of a mechanism that will not extend 15 beyond the clearance limits to which it is necessary to work in designing modern railway equipment.

Another object is to provide, in combination with a side dump car, a door arrangement wherein the doors will be held shut by 20 means of a simple mechanism that may be readily released when it is desired to discharge the lading from the car.

Another object is to provide a railway car 25 having a series of hoppers along its sides with spaces between these hoppers, which will be outside of the lading cavity of the car, and to arrange within these cavities, and secured directly to the end walls of the 30 hoppers, door retaining devices which may be operated to release or close a single door without allowing the discharge of the contents of the car from any other door.

It is necessary in cars of this character 35 that the doors be held firmly shut, and to this end, it is desirable to support each door from both ends thereof. It is also desirable in many instances that but one door at a time be opened to permit the discharge of 40 the lading. One of the objects of the present invention is to provide a car and door device constructed to meet these conditions.

With such general and other more specific objects in view, the invention consists of the 45 formation, combination and arrangement of parts as will be herein described and particularly claimed.

In the accompanying drawings, which 50 show a preferred embodiment of the invention, Figure 1 is a fragmentary side elevational view of a car body constructed in accordance with the principles of the present invention. Figure 2 is a fragmentary transverse vertical section through the same, this 55 view being taken on the line 2—2 of Figure 1. Figure 3 is a partial end elevational view

of a car of the same construction, this figure being drawn to a reduced scale over that of Figures 1 and 2. Figure 4 is a longitudinal vertical section taken through a portion of the door-securing mechanism, this view being taken on the line 4—4 of Figure 2. Figure 5 is a transverse horizontal sectional view, this view being taken approximately on the line 5—5 of Figure 2.

Referring now to these drawings, the car is shown as having sides 1 with outwardly swinging doors 3 pivoted to the car body, the hinge edges of the doors being near the lower edges of the car sides 1, and the outwardly swinging free edges thereof being near the rail. These doors extend longitudinally of the car body and are hinged thereto at 2, body hinge plates such as 6 being employed. These hinge plates may be 75 affixed to any suitable part of the car body, the intent in the present embodiment being that the lowermost edges of the side plates 1 shall be pressed, while hot, into the necessary shape to conform to and form seats for 80 these hinge plates, as well as for the usual side stakes which are applied to such car bodies. The portion of the side plate 1 against which the hinge plates 6 seat may lie in a different plane from the general 85 plane of the car side and preferably the hinge plates 6 are located near the lower ends of the side stakes and these hinge plates are preferably between the lower ends of the side stakes, so that the load from the 90 hinge plates 6 may be transferred to the side stakes without undue straining of the car side plate, or of the portion of the car structure to which the hinge plates 6 are applied.

In Figure 3, one of these doors is shown 95 in closed position and another door is shown in partially open position. The slope sheet 4 of the car is constructed in sloping fashion to provide discharge hoppers along each side of the car, the doors 3 being arranged 100 to close the outwardly facing openings of these hoppers. This hopper construction permits the discharge of the lading of the car to points alongside of the track. A plurality of these hoppers, which are indicated at 5, are formed along each side of the car, each hopper opening being closed by an individual door 3. The aforesaid hinge plates such as 6 may be secured, as by means of rivets 7, to the side of the car 110 body, with co-operating hinges such as 8 affixed to each door as by means of rivets

9. Hinge pintles, such as 10, may be utilized for connecting the door and body hinges, these pintle rods preferably extending continuously for all the hinges of a door 5 and lying longitudinally of the car along the outer face of the car side. Between adjacent hoppers there is formed a cavity 11, this cavity being defined by hopper and sheets such as 12. The end sheet 12 of one 10 hopper is spaced somewhat from the adjacent end sheet 12 of the next hopper, so that the cavity 11 is thereby produced. The end sheets 12 may be brought together above the cavity 11 as at 13, and be there connected in 15 any desired manner to form a hood over the cavity.

The door 3 of each hopper covers the full face of the hopper opening and the ends of the door plate preferably extend slightly 20 beyond the end limits of the hopper opening, so as to overlap the edges of the hopper opening to prevent loss of lading from imperfectly fitted doors. Extending across the outer face of each door and near the lower 25 edge of the same is a stiffening member 14. These members are in the present embodiment formed of channel irons which are secured to the door plates by means of rivets 15. These channels do not extend for quite 30 the full length of the door plate, and secured to the ends of the same are short lengths of angle iron 16, securing rivets such as 17 passing through these angles and the channels 14 of the door plates. These angles 35 extend outwardly at each end of the doors to slightly beyond the edges of the doors, so that the projecting ends constitute locking faces, which may be engaged by suitable door supporting means. By this 40 construction, the doors may be supported at each end, and near the lower edges of the doors, the hinges at the tops of the doors constituting efficient securing means for the upper edges of the doors. This construction 45 is economical in cost, especially where the device is applied to old cars.

The road clearances limit the width of the car near the rail to such an extent that great care must be taken in the construction 50 of the parts, if the lading space of the car is to be carried out to reasonable lines. In the present construction the stiffening member 14 is formed of a structural channel with its back laid against the outer face of 55 the door and with its two flanges outstanding from the door. The angles 16 need not have so great a moment of resistance as the channel 14, as the latter spans a greater distance and is accordingly subjected to greater 60 bulging moments. The single outstanding leg of the angle 16 is sufficient to meet the duty imposed upon it, as compared with the two outstanding portions of the channel 14. At the same time the parts are kept within 65 reasonable clearance limits.

In order that the doors may be properly supported in closed position, a door supporting hook 18 is pivoted upon the outer face of each end sheet of each hopper. These hooks lie substantially against the outer 70 faces of these end sheets, and swing upwardly along these sheets to release the doors and downwardly to engage the locking faces on the doors for holding the latter shut. A suitable pivoting bracket such as 19 may be 75 used, and the pawl or cam 22 may be utilized to hold the locks in engagement with the doors. The brackets, together with the hooks and the pawls, may be held in operative association and be affixed to the hopper 80 end sheets by means of suitably arranged rivets such as 20. There are thus direct connections between the hopper end sheets and the doors, so that, by the absence of intervening parts, there is less likelihood of 85 failure of the parts to function as desired to hold the doors tightly against the hopper mouths.

It will be noted that the pivot pins of the hooks 18 are set back somewhat from the 90 side of the car, and that the end of the hooks project only a small amount beyond the outer face of the hopper. This keeps the door securing mechanism within the close limits required where third rail electric 95 clearances must be observed. At the same time, by arranging the door securing mechanisms within the cavities 11, and especially by applying a securing member upon each 100 end sheet of each hopper, the doors may be held securely shut by a very inexpensive device that connects the door directly to the member, (the end plate of the hopper) 105 against which the fit is desired. At the same time, any door may be released without the release of the other doors. The road clearances above referred to are at the same time observed, and the use of complicated inside winding arrangements or other expensive 110 means for effecting these results are avoided.

In order that the hooks 18 may swing closely along the outer faces of the hopper end sheets, the door plate is notched as at 21 to permit the necessary swing of the hooks to release the doors. This reduces 115 the bulging moments, and also makes the door hooks 18 accessible without the necessity of making the cavities 11 of great width.

The construction, an embodiment of 120 which is thus described, constitutes an extremely simple and reliable means of securing the doors of side dump cars, and avoids the complicated rigging that is frequently employed for this purpose. In operating the present device it is only necessary to push the doors shut with the foot, when the hooks will drop into position behind the upright legs of the angles 16, and the doors will be held effectively shut. To 130

release the doors it is only necessary to rotate the cams 20 to a suitable position, when the hooks 18 may be driven up and the weight of the lading behind the doors will 5 cause them to swing open, permitting the discharge of the contents of the cars desired.

I have thus described an embodiment of my invention. Other embodiments are contemplated within the scope of the appended 10 claims without departing from the spirit of the same.

What is claimed is:

1. A railway car having a plurality of individual hoppers formed along each side 15 thereof, hopper end sheets defining the end limits of the individual hoppers, the end sheets of adjacent hoppers being spaced slightly from each other to form cavities between the hoppers, doors hinged to the 20 hoppers along the upper edges thereof, a door-securing hook for each end of each door, the same being pivoted against the outer faces of the end sheets of the corresponding hopper and being disposed within 25 the said cavities, and brackets overlying the said hooks and secured to the hopper end sheets.

2. A railway car having a plurality of individual hoppers formed along each side 30 thereof, hopper end sheets defining the end limits of the individual hoppers, the end sheets of adjacent hoppers being spaced slightly from each other to form cavities between the hoppers, doors hinged to the hop- 35 pers along the upper edges thereof, and a door securing hook for each end of each door, the same being pivoted upon the end sheets of the corresponding hoppers and disposed within the said cavities.

40 3. A railway car having a plurality of individual hoppers formed along each side thereof, hopper end sheets defining the end limits of the individual hoppers, the end sheets of adjacent hoppers being spaced 45 slightly from each other to form cavities between the hoppers, doors hinged to the hoppers along the upper edges thereof and ar- ranged to swing outwardly into open pos- 50 tion, door-securing members for each end of each door, the same being pivoted upon

the outer faces of the hopper end sheets and within the said cavities therebetween, and members carried by the doors near the ends thereof, arranged to over-reach the ends of the said hoppers, the same being formed for 55 co-operation with the said door-securing members.

4. A railway car having a plurality of in- 60 dividual hoppers formed along each side thereof, hopper end sheets defining the end limits of the individual hoppers, the end sheets of adjacent hoppers being spaced slightly from each other to form cavities between the hoppers, doors hinged to the hoppers along the upper edges thereof and 65 arranged to swing outwardly into open po- sition, the ends of said doors slightly over- reaching the ends of the corresponding hop- 70 pers, door-securing members for each end of each door the same being arranged for move- 75 ment along the outer faces of the hopper end sheets, and being pivotally associated be- 80 tween the ends of the doors and the hopper end sheets in such manner as to hold for re- lease the doors, the said door-securing mem- bers lying in planes substantially within the normal limits of swing of the doors, and the doors being notched out at their ends to clear said door-securing members.

5. A railway car having a hopper formed 80 along one side thereof near the bottom of the car, a door hinged to the car above the hopper and arranged to be swung outwardly from the hopper opening into open po- 85 sition, means operatively associated between the door and the ends of the hopper for holding the door in closed position against the mouth of the hopper, said means including a stiffening member secured to the door near the lower edge thereof, the same being 90 formed of a channel section with the flanges thereof extending outwardly from the door, and flanged arms also secured to the door, the same extending beyond the end limits of the door and being arranged for co-operation 95 with door securing members carried by the car body.

In testimony whereof I affix my signature.

JOHN A. PILCHER.
